ARRANGEMENT FOR HOLDING REMOVABLE
DENTAL PROTHESIS APPARATUS IN THE
MOUTH

Alfredo Fiorentini, Nice, France

Application January 8, 1948, Serial No. 1,262
In Italy January 4, 1947Section 1, Public Law 690, August 8, 1946
Patent expires January 4, 1967

6 Claims. (CL. 32—5)

1

My invention has for its object an arrangement for holding removable dentures in the mouth and its essential feature consists in that it includes a male part adapted to be welded to the metal crown capping a sound tooth and a female part partly embedded in the denture and formed with a groove adapted to move over a projection of the male part and held in position by the pressure exerted at the lower end of said projection by a ball submitted to the pressure of a helical spring.

This arrangement allows the easy positioning and removal of the denture by the person carrying it and makes its accidental displacement or removal impossible, providing thereby complete reliability.

I have illustrated diagrammatically in accompanying drawings and by way of example a preferred embodiment of my invention. In said drawings:

Fig. 1 is an elevational view of the complete arrangement, the crown shown in Fig. 2 and Fig. 4 being omitted.

Fig. 2 is a cross-sectional view through line II—II of Fig. 1;

Fig. 3 is a horizontal cross-sectional view through line III—III of Fig. 2 seen in the direction of the arrows;

Fig. 4 is a horizontal cross-sectional view of a modification;

Fig. 5 is a longitudinal sectional view through line V—V of Fig. 2, the female part being ready for insertion over the male part shown in an elevational view;

Fig. 6 is a transversal cross-section of the male part;

Fig. 7 is a transversal cross-section of the male part of a modification;

Fig. 8 is a plan view; and Fig. 9 is a side view of a modified member adapted to replace the ball shown in Fig. 2.

According to the embodiment illustrated in Figs. 1, 2 and 3, the male portion of the arrangement is constituted by a projection 1 assuming a dove-tailed or like suitable cross-section and extending at the rear of a capping 3 throughout its height and secured thereto by a part 2 with an inner rounded wall and showing a tapering terminal cross-section; the shape of this part is designed in a manner such that it may be welded to the metal crown capping 3 or a sound tooth forming a pillar and illustrated broken lines. Said part shows a large contacting surface ensuring a perfect weld.

The female portion is embedded inside the

2

denture illustrated in broken lines in Fig. 2. It is constituted by a locking member 4 showing on the side adapted to come into contact with the male part a groove 5 the cross-section of which conforms to that of the projection over which it is to be fitted. The operative wall of the groove 5 on the side facing the extension 2 is shorter than the opposite wall and its location is shifted rearwardly so as to allow the passage of said extension. The lower part of the female locking member 4 is formed with a channel 6 containing a ball 7 urged towards groove 5 by the helically wound spring 8. Said channel opens into groove 5 through a port of restricted area preventing the passage of the ball through it, while the opposite end of the channel is closed by the screw 9 against which the spring 8 abuts. The channel is furthermore in communication with the atmosphere through a small channel 10 passing through the sidewall of the denture; said channel serves for the washing of the passage 6 of the ball and of the spring.

The locking member 4 may include over part of its height (Fig. 3) a lateral projection 11 for securing thereto a plate 11' that may simulate the front surface of a tooth. Said plate conceals the part of the locking member adjacent the pillar tooth. The remainder of the locking member is embedded inside the denture. According to the material used for the apparatus, the block may be completely or only partly embedded therein.

Obviously the screw 9 may be replaced by a plate 12 screwed over the locking member (Fig. 4) or through any other stop.

Similarly, any other part assuming a rounded shape at its end such as that illustrated at 13 in Figs. 5, 8 and 9 may be used instead of a ball.

The projection and the groove may also assume a V-shaped, or any other suitable, cross-section as desired.

The apparatus is held in place through the ball 7 that exerts a pressure on the projection and urges the lateral faces of the latter against those of the groove, which prevents any undesired release. The pressure of the ball is resilient due to the presence of the helical spring 8.

The chief components of the apparatus are preferably made of inoxidizable metal, but they may be made as well of any other material and they may also assume any other desired shape or size.

What I claim is:

1. In a locking means for removable dentures, in combination, a capping adapted to fit over a natural tooth; a projection on said capping ex-

tending substantially the total height of said capping and having substantially identical transversal cross-sections perpendicular to the height, said cross-sections being restricted near the capping; a locking member adapted to be rigidly secured to a denture, said locking member having a groove of the same transversal cross-section as that of the projection on said capping and being slidably engaged by said projection, said locking member having a channel extending substantially at right angles to and communicating at one end thereof with said groove, said channel being slightly restricted at said one end near the groove; and a spring-loaded element slidably arranged in said channel adjacent said groove and projecting into the same but retained by the restricted end of said channel, whereby when the locking member is slid in place over said projection, said element will be spring-pressed against said projection, thereby frictionally engaging the same.

2. In a locking means for removable dentures, in combination, a capping adapted to fit over a natural tooth; a projection on said capping extending substantially the total height of said capping and having substantially identical transversal cross-sections perpendicular to the height, said cross-sections being restricted near the capping; a locking member adapted to be rigidly secured to a denture, said locking member having a groove of the same transversal cross-section as that of the projection on said capping and being slidably engaged by said projection, said locking member having a channel extending substantially at right angles to and communicating at one end thereof with said groove, said channel being slightly restricted at said one end near the groove; a spring-loaded element slidably arranged in said channel adjacent said groove retained therein by the restricted end of said channel, said element being rounded at the side facing said groove, said locking member having a second channel extending substantially at right angles to the first channel and in communication with said first channel and atmosphere.

3. In a locking means for removable dentures, in combination, a capping adapted to fit over a natural tooth; a projection on said capping extending substantially the total height of said capping and having substantially identical transversal cross-sections perpendicular to the height, said cross-sections being restricted near the capping; a locking member adapted to be rigidly secured to a denture, said locking member having a groove of the same transversal cross-section as that of the projection on said capping and being slidably engaged by said projection, said locking member having a channel extending substantially at right angles to and communicating at one end thereof with said groove, said channel being slightly restricted at said one end near the groove; an element having a rounded face slidably arranged inside said channel retained therein by the restricted end of said channel and facing said groove with its rounded face; a spring forcing said element towards said groove; and means for retaining said spring.

4. In a locking means for removable dentures, in combination, a capping adapted to fit over a natural tooth; a projection on said capping extending substantially the total height of said capping and having substantially identical transversal cross-sections perpendicular to the height, said cross-sections being restricted near the capping; a locking member adapted to be

rigidly secured to a denture, said locking member having a groove of the same transversal cross-section as that of the projection on said capping and being slidably engaged by said projection, said locking member having a channel extending substantially at right angles to and communicating at one end thereof with said groove, said channel being slightly restricted at said one end near the groove and provided with a screw thread at its other end; a ball slidably arranged inside said channel retained therein by the restricted end of said channel; a spring forcing said ball towards said groove; and a screw adapted to be threaded into the screw thread at the other end of said channel and to retain said spring.

5. In a locking means for removable dentures, in combination, a capping adapted to fit over a natural tooth; a projection on said capping extending substantially the total height of said capping and having substantially identical transversal dovetailed cross-sections perpendicular to the height; a locking member adapted to be rigidly secured to a denture, said locking member having a groove of the same transversal cross-section as that of the projection on said capping and being slidably engaged by said projection, said locking member having a channel extending substantially at right angles to and communicating at one end thereof with said groove, said channel being slightly restricted at said one end near the groove; and a spring-loaded element slidably arranged in said channel adjacent said groove retained by the restricted end of said channel, said element being rounded at the side facing said groove, whereby when the locking member is slid in place over said projection, the rounded side of said element will be spring-pressed against said projection, thereby frictionally engaging the same.

6. In a locking means for removable dentures, in combination, a capping adapted to fit over a natural tooth; a projection on said capping extending substantially the total height of said capping and having substantially identical transversal cross-sections perpendicular to the height, said cross-sections being restricted near the capping; a locking member adapted to be rigidly secured to a denture, said locking member having a groove of the same transversal cross-section as that of the projection on said capping and being slidably engaged by said projection, said locking member having a channel extending substantially at right angles to and communicating at one end thereof with said groove, said channel being slightly restricted at said one end near the groove; a spring-loaded element slidably arranged in said channel adjacent said groove retained therein by the restricted end of said channel, said element being rounded at the side facing said groove; and means on the front face of said locking member adapted to hold a false tooth front.
